[57] CLAIM

The ornamental design for a cover for a pick-up tool jaw, as shown and described.

DESCRIPTION

FIG. 1 is a perspective view of a cover for a pick-up tool jaw showing my new design;

FIG. 2 is a front elevational view thereof shown in an open position;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines showing the cover for a pick-up tool jaw, the hand, and the broken bottle in FIG. 1 are for illustrative purposes only and form no part of the claimed design.

FIG. 6

FIG. 4

FIG. 3

FIG. 5

FIG. 7
